COACH FOR PICK-UP TRUCKS

Steve P. De Gennaro and Steve J. De Gennaro, both of 6301 Industrial Ave., Riverside, Calif.

Filed Feb. 28, 1963, Ser. No. 73,753

Term of patent 14 years

(Cl. D14—3)

The portions shown in broken lines in FIG. 1 are included for illustrative purposes only. The side not shown is a mirror image of the side shown.

We claim:

The ornamental design for a coach for pick-up trucks, substantially as shown and described.
